JOSEPH L. HEWES.
Stop-Valves for Water-Pipes.

No. 127,768. Patented June 11, 1872.

Inventor.
Joseph L. Hewes.

UNITED STATES PATENT OFFICE.

JOSEPH L. HEWES, OF NEWARK, NEW JERSEY.

IMPROVEMENT IN STOP-VALVES FOR WATER-PIPES.

Specification forming part of Letters Patent No. 127,768, dated June 11, 1872.

SPECIFICATION.

To all whom it may concern:

Be it known that I, JOSEPH L. HEWES, of the city of Newark, county of Essex, and State of New Jersey, have invented a new and Improved Water-Stop; and I do hereby declare that the following is a full and exact description of the same, reference being had to the accompanying drawing and to the letters of reference marked thereon.

The object of my invention is to overcome a difficulty commonly existing in the practical working of the stops, as heretofore made. Persons having experience in the care and management of water-works, especially, are familiar with the difficulty experienced whenever it becomes necessary to shut off a line of pipes for repairs, or for the purpose of making connections, by the failure of the stops to close with any degree of tightness, rendering it necessary oftentimes to do the proposed work with a stream of water running. This occurs usually, not through any defective workmanship in the stop, but because of obstructions which prevent the gate from being closed. Through the carelessness of workmen and other causes a line of pipes, in being laid, is liable to collect a considerable quantity of sand, gravel, and other sedimentary deposit, which the action of a current of water sweeps along and deposits in the depression, or that part of the chamber in which the valve works, lying below the lower surface of the water-way. This is inevitable, and when once lodged there no amount of power applied to the valve will force it to find its seat with any degree of accuracy. The whole stop is strained or broken in the attempt to close the valve, and it is condemned as worthless.

The nature of my invention consists in so forming and arranging the lower end of the valve, the water-ways, and passage beneath and around the valve, as to secure the passage of a concentrated current of water through the sediment collected, as before set forth.

To enable others skilled in the art to use my invention, I will proceed to describe its construction and operation.

I construct the shell or case of the stop according to any of the forms in use among makers of such work, and the valve or gate

may be substantially of any of the forms heretofore adopted. The form of neither of these is essential. Neither is the mode of operating the valve.

Figure 1 of the drawing represents a sectional end view, and Fig. 2 a longitudinal section of my improved water-stop.

I construct the gate or valve B with one side or face somewhat longer than the other, so that when the valve has been so far depressed that the longer face entirely covers its corresponding opening or water-way the other or opposite face will not quite cover its water-way, thus leaving a passage for the water under and by the shorter face. The same object may be accomplished by raising the bottom of the water-way C on one side of the valve slightly above that on the other, and again by extending the center of the valve below the faces thereof.

I do not confine myself to the use of either of these means, and only particularly describe that which seems best adapted to effect the desired object.

From the chamber in which the valve works, and immediately under the valve, I construct a passage, A, descending and passing outside of the shell or case and entering the bottom of the water-way beyond the longer face of the valve, forming a communication from the water on one side of the valve to the recess or depression under the valve, in which depression, as before set forth, the lodgment of sediment occurs.

The operation of the stop is as follows: The valve being opened, the pipe filled with water, and the bottom of the chamber receiving the sediment carried along by the current, we wish to shut off the water by lowering the valve. When the water-way adjacent to the long side of the valve is covered that next to the short side still presents some opening through which the water flows. It rushes through the contracted opening and through the only course for it—the passage A—and into the water-way on the opposite side of the valve. Whichever direction the water has the result is the same in either case, removing, by the force of the current, anything which may have lodged below the valve, leaving for it a clear and unobstructed course. The form or shape of the pas-

sage A is immaterial, only requiring to be so constructed and arranged as to pass through it any obstruction liable to lodge under the valve.

Having thus set forth the nature and object of my invention, what I claim, and desire to secure by Letters Patent, is—

1. The valve or gate B for water-stops, constructed with one side or face longer than the other, substantially in the manner and for the purpose described.

2. I claim the use, in connection with a water-stop having a direct water-way and a valve working entirely across and closing said water-way, of an independent and separate pas-

sage extending from the chamber immediately below the valve, passing outside of the shell or case of the stop, and communicating with the main water-way beyond the valve, substantially in the manner and for the purpose described.

3. The combination of a valve, B, and passage A with the shell or case of the stop and its water-ways, the whole arranged substantially in the manner and for the purpose described.

JOSEPH L. HEWES.
